Primary Examiner — Cynthia M. Chin

(57) **CLAIM**

The ornamental design for an electric scooter, as shown and described.

DESCRIPTION

The patent or application file contains at least one drawing executed in color. Copies of this patent or patent application publication with color drawing(s) will be provided by the Office upon request and payment of the necessary fee.

1. Electric scooter

1.1: Front

1.2: Back

1.3: Left

1.4: Right

1.5: Top

1.6: Bottom

1.7: First Perspective View

1.8: Second Perspective View

1.9: Third Perspective View

The broken lines shown in the reproductions and the portions of the design shown in the color red are for the purpose of illustrating portions of the scooter that form no part of the claimed design.
